UNITED STATES PATENT OFFICE.

NOWELL F. SAWYER, OF BRADFORD, MASSACHUSETTS.

STEAM-BOILER.

SPECIFICATION forming part of Letters Patent No. 360,953, dated March 29, 1887.

Application filed January 10, 1887. Serial No. 223,876. (No model.)

To all whom it may concern:

Be it known that I, NOWELL F. SAWYER, a citizen of the United States, and a resident of Bradford, in the county of Essex and State of Massachusetts, have invented new and useful Improvements in Steam-Boilers, of which the following, taken in connection with the accompanying drawings, is a specification.

Figure 1 represents a longitudinal section of the invention, and Fig. 2 represents a cross-section on the line A. B, shown in Fig. 1.

Similar letters refer to similar parts wherever they occur on the different parts of the drawings.

The invention is equally well adapted for use as a steam generator or boiler, steam-heating or hot-water circulating device, and it is carried out as follows:

a is the hollow water-front, made of cast-iron and provided with fuel-feed opening b and door b', and ash-pit opening c, having hinged door c', as shown in Fig. 1. From the back of the hollow water-front a extends backward the hollow water-compartments a' a', which form the sides of the fire-box, and such compartments have their tops a" a" made tapering—that is, rising from the rear of the fire-box toward the hollow water-front a, as shown, so as to cause a constant circulation of the water in said chambers or compartments from the lower to the upper portion of the hollow water-front a, with which they are in open and free communication, as shown.

d is the grate of the fire-box, and e is the bridge-plate at the rear of the latter, such bridge-plate being extended below the grate, and made to rest on the plate f, that forms the bottom of the ash-pit C, as shown.

c" c" are suitable bolts, beams, or stays for supporting the plate f, as shown in Fig. 1.

E represents the brick-work at the rear of the fire-box, as shown in the drawings.

g g g represent a series of U-shaped tubes or pipes, the ends of which are suitably connected and secured to the rear wall of the hollow water-front a, as shown, said pipes having their lower portions made horizontal, or nearly so, and having their upper legs made inclined—that is, rising from the rear toward the water-front a, as shown in Fig. 1, so as to cause a

circulation of the water in said U-shaped tubes from the lower to the upper portion of the hollow water-front, as shown by arrows in said pipes in Fig. 1. The fire-box is located, as shown, between the lower and upper legs of the said circulating-pipes g g g. 55

Within the hollow water-front a are made a pair of division-walls, a³ a³, outside of the water-compartments a' a', as shown in Fig. 2, said walls a³ a³ terminating at some distance from the top and bottom of the water-front a, as shown.

a⁴ a⁴ are the steam-pipes leading from the upper portion of the hollow water-front a, and a⁵ a⁶ represent, respectively, the feed-water pipe and blow-off pipe connected to the lower portion of the hollow water-front, as shown.

By the construction and arrangement of the circulating U-shaped pipes g g g, secured to the rear of the hollow water-front a, as shown, 70 said pipes are made free to expand or contract in any direction without in any manner causing a strain on the water-front a, and thus all liability of breakage or explosion of the boiler is prevented. h is the brick-work, within which 75 the water-front and circulating-pipes are enclosed, and i represents the chimney or smoke-stack, having openings k l leading to it from the combustion-chamber, such openings being provided with the respective dampers k' l', as shown in Fig. 1. At some distance above the upper inclined legs of the circulating-pipes g g is located the inclined deflecting plate or cover m, (shown in Fig. 1,) which plate is arranged parallel, or nearly so, to the upper inclined portions of the said circulating-pipes g g g, as shown in Fig. 1. Said cover m is preferably supported on beams, rods, or stays m' m', and covered on top by means of asbestos or bricks m", as shown in Fig. 1. The object of 85 such inclined plate or cover m is to cause the heat from the fire-box to rise to the highest portion of the combustion-chamber, and thereby to cause a free combustion of the gaseous products of the fuel and to bring the latter in close and intimate contact with the circulating-pipes g g g, and thus to obtain the best results for heating the water and circulating the same within the various parts of the boiler.

Below the horizontal legs of the circulating- 100

pipes $g g g$, I arrange a division-plate, n , preferably supported on beams, stays, or braces $n' n'$, as shown in Fig. 1, said plate being extended to the rear close up to the chimney i , with a space 5 left between its forward end and the rear of the lower portion of the water-front a , as shown in Fig. 1, thus forming flues $o p$, leading from the combustion-chamber to the chimney i , as shown in Fig. 1. The lower horizontal legs of 10 the circulating-pipes $g g g$, as is seen in Fig. 1, are thus arranged and located within the flue or channel o , causing the products of the fire-pot and combustion-chamber to pass around and between said pipes on their way to the 15 chimney i , as shown by arrows in Fig. 1, thus obtaining the best results for heating and circulating the water in said pipes $g g g$ to and from the hollow water-front a .

$a' a'$ are man-holes, as usual, in the forward 20 part of the hollow water-front a , and $a^8 a^8$ are covers for the same, as shown in Fig. 1.

Having thus fully described the construction, operation, and arrangement of my invention, I wish to secure by Letters Patent and 25 claim—

1. In a steam-generator, the hollow water-front a , having the rearwardly-projecting hollow water-chambers $a' a'$, adapted to form the sides of the fire-box, and having the inclined 30 tops $a'' a''$, for the purpose of causing a proper circulation of the water within said chambers $a' a'$, as set forth.

2. In a steam-generator, the hollow water-

front a , having the vertical division-walls $a^3 a^3$, as described, combined with the hollow water-chambers $a' a'$, and U-shaped circulating-pipes $g g g$, connected to the rear of the water-front a , as and for the purpose set forth. 35

3. In a steam-generator, the hollow water-front a and the U-shaped circulating-pipes $g g g$, connected to the rear of said hollow water-front, in combination with the fire-box arranged between the upper and lower legs of 40 said U-shaped circulating-pipes $g g g$, as set forth. 45

4. In a steam-generator, the hollow water-front a and the U-shaped circulating-pipes $g g g$, connected to it, as described, in combination with the plates $f n$ and flue o , in which the lower legs of the circulating-pipes $g g g$ are contained, as and for the purpose set forth. 50

5. In a steam-generator, the hollow water-front a and the U-shaped circulating-pipes $g g g$, as described, in combination with the inclined cover m , for conducting the products of 55 the fire to the highest portion of said circulating-pipes, and the return-flue o , for heating the lower portions of said pipes $g g g$, as set forth.

In testimony whereof I have signed my name to this specification, in the presence of two 60 subscribing witnesses, on this 7th day of January. A. D. 1887.

NOWELL F. SAWYER.
